UNITED STATES PATENT OFFICE.

ROBERT W. ALLERTON, OF SOUTH ORANGE, NEW JERSEY, ASSIGNOR TO WORTHINGTON PUMP AND MACHINERY CORPORATION, OF NEW YORK, N. Y., A CORPORATION OF VIRGINIA.

SAFETY BACKFLOW VALVE FOR CONDENSER SYSTEMS.

Application filed December 22, 1920. Serial No. 432,419.

To all whom it may concern:

Be it known that I, ROBERT W. ALLERTON, a citizen of the United States, residing at South Orange, county of Essex, and State 5 of New Jersey, have invented certain new and useful Improvements in Safety Back-flow Valves for Condenser Systems, fully described and represented in the following specification and the accompanying drawings, forming a part of the same.

This invention relates to improvements in back-flow valves for condenser systems.

It is the especial object of the present invention to provide improved automatic 15 means for preventing the flooding of condensers provided with hydraulic vacuum pumps or ejectors, such means operating on stoppage or inefficient pump or ejector action, to shut off the condenser from back 20 flow of the pump liquid and thus permit continuous operation of the condenser. The invention is especially applicable to high vacuum condensers in which the air and uncondensed vapors are taken off separately 25 from the water of condensation, but is of general application in condenser systems.

It is a further object of the invention to so arrange such back-flow valve and its operating mechanism that the valve is normally wholly or substantially outside of the 30 air passage and will not, therefore, obstruct or choke such passage under normal operating conditions, such valve obstructing the air passage only to shut off back-flow.

For a full understanding of the invention, a detailed description of a preferred embodiment of the same will now be given in connection with the accompanying drawings, and the features forming the invention 35 then specifically pointed out in the claims.

In the drawings:

Figure 1 is a side elevation, partly in section, of a condenser system embodying the 40 invention;

Figure 2 is a vertical section on the line 2-2 of Fig. 1 of the back-flow valve and its operating mechanism, and

Figure 3 is a similar view looking to the 45 right in Fig. 2.

Referring now to the drawings, and particularly to Fig. 1, the letter A indicates a condenser of the surface type provided with the usual hot-well B and condensate pump

C and connections therefor; D indicates the 55 air and uncondensed vapor connection between the condenser and a hydraulic vacuum pump indicated generally by the letter E, and F is the centrifugal circulating pump therefor delivering through nozzle H 60 to supply tank I provided with vent pipe a. The general system indicated is the same as shown and described in Letters Patent No. 1,255,869, dated February 12, 1918, and the 65 hydraulic pump that of Letters Patent No. 1,031,143, dated July 2, 1912, but it will be understood that the invention may be applied in connection with other systems and hydraulic pumps or ejectors of other types.

In order to prevent flooding of the condenser A, by back-flow of the pump liquid thereto, which may result from various causes, such as pump trouble or shortage of pressure water, I interpose in the connection 70 D between the condenser A and the hydraulic air discharge pump E, an automatic shut-off or back-flow valve 10 (Fig. 3) mounted in a suitable casing 11, such valve being hinged in the casing by pivot rod 12 75 and cooperating with trip mechanism by which it is held open under normal working conditions, such trip mechanism comprising an L-shaped latch piece pivoted on bracket 15 in the valve casing and having 80 arms 13, 13', one arm 13 being so shaped as to engage the edge of the valve 10 and hold it open, and the other arm 13' being connected by link 17 to a lever 19 pivoted on a bracket 21 within the valve casing. 85 The longer end of the rocking lever 19 carries a ball-float 1. It has been found preferable to allow a small quantity of water to remain in the casing 11 so as to hold the ball-float slightly elevated, any lessening of 90 such water by evaporation merely tending to hold the latch arm 13 more firmly in contact with the valve 10.

It will be apparent from the foregoing 95 that when any condition arises tending to impair the efficiency of the hydraulic air pump, any back-flow of pump liquid will first flow into the valve casing 11, thereby raising the ball-float 1 and, through the connections above described, the latch 13 will 100 be released from engagement with the valve 10 and the latter will drop by gravity to its seat, as shown in dotted lines in Fig.

3, where it will be held by the excess pressure on the pump side of the valve, or its own weight due to the incline of the valve seat, until it is manually raised by a handle 2 outside the valve casing on the rod 12.

When the valve has been closed as above described and it is desired to open the same, the screw plug 5 is removed and the water in the valve casing allowed to drain off to the level of the plug and the ball-float 1 drops to its lowermost position. The screw plug 5 is then replaced and handle 2 forced upward, carrying with it the valve 10 until the latter passes the latch arm 13 so as to be held thereby.

It will be understood that various changes may be made in the construction shown and described within the scope of the claims, and that, while the invention has been shown and described in connection with the air discharge system of a surface condenser, it may be used with advantage in jet condensers and in other relations where such back-flow valves are applicable.

What is claimed is:

1. The combination with a condenser system having a hydraulic air discharge pump of the like, of a valve normally permitting free flow of air and vapor through the connection from the condenser to said pump, and means for automatically closing said valve to prevent back-flow of liquid to the condenser.

2. The combination with a condenser system having a hydraulic air discharge pump

or the like, of a valve normally permitting free flow of air and vapor through the connection from the condenser to said pump, and means controlled by back-flow of liquid in said connection for closing the valve.

3. The combination with a condenser system having a hydraulic air discharge pump or the like, of a valve normally permitting free flow of air and vapor through the connection from the condenser to said pump, and float controlled means for closing said valve on back-flow of pump liquid in said connection.

4. The combination with a condenser system having a hydraulic air discharge pump or the like, of a valve on the connection between the condenser and said pump, valve trip mechanism normally holding said valve open, and means for causing said trip mechanism to release said valve and allow it to close by gravity on back-flow of liquid in said connection.

5. The combination with a condenser system having a hydraulic air discharge pump or the like, of a float chamber in the connection between the condenser and said pump, a valve controlling the connection, a latch for normally holding said valve open, and a float and connections for tripping said latch to allow said valve to close by gravity on back-flow of liquid to said float chamber.

In testimony whereof, I have hereunto set my hand.

ROBERT W. ALLERTON.
